REGULATING MECHANISM

Original Filed Dec. 4, 1926 3 Sheets-Sheet 3

UNITED STATES PATENT OFFICE

JAMES D. SPILLANE, OF BRONX, NEW YORK, ASSIGNOR TO THE CONSTANTATOR CO., INC., OF NEW YORK, N. Y., A CORPORATION OF NEW YORK

REGULATING MECHANISM

Application filed December 4, 1926, Serial No. 152,609. Renewed November 30, 1929.

This invention relates to improvements in regulating mechanism,—as, for example, mechanism adapted for controlling fluid pressures, volumes, temperatures, etc., in various apparatus, especially for industrial uses.

An important object of the invention is to provide a regulating mechanism which will be extremely simple in construction and much more reliable and sensitive than such devices of the prior art.

In my application for U. S. Letters Patent for Motive power regulators, Serial No. 648,134, filed June 2, 1923, a practical mechanism has been disclosed wherein a control member, which is influenced by conditions to be governed, is adapted to actuate, preferably, a switch which initiates compensation for variations in the controlled conditions, and the switch is adapted to follow up the control member and be reset thereby when the condition which influenced the control member has been corrected. In that case the invention is illustrated as applied to a damper regulator for a steam boiler, though not restricted to such use, and includes a motor-driven actuating rod connected to the damper, and its motor being controlled preferably by the above mentioned switch. The switch is bodily reciprocated by a swinging arm connected to the actuating rod, the construction being such that the switch has less amplitude of movement than the rod by virtue of the fact that it is closer to the pivotal center about which the connecting arm swings.

The present invention embodies certain improvements in the art, and particularly over the apparatus disclosed in the above identified application, and provides a similar apparatus with a greater range of movement for the switch, or a substituted control member, and a longer control member resulting in greater sensitivity. More specifically, the swinging arm which imparts movement to the switch or its substitute in the prior application is eliminated, and the switch or its substitute of this application is carried by the actuating rod. For this purpose the actuating rod may be provided with a supporting bracket to which the switch or its substitute

may be attached, and said bracket may also function to hold the actuating rod against rotation.

Another object of the invention is to provide a regulator as a complete unit with suitable adjustments for the various parts, whereby a standard unit will be capable of a wide variety of industrial applications and under different conditions.

Still another object is to provide such a device wherein the control member is yieldably connected in such a manner that sudden shocks will be absorbed without doing injury to the switch or other parts, and whereby slight non-essential fluctuations of the control member will have no effect in the actuation of the switch.

With these and other objects and advantages in view, the invention resides in the novel features of construction, combination and arrangement of parts hereinafter set forth, shown by way of illustration in the accompanying drawings, and specifically pointed out in the appended claims.

In the drawings, Figure 1 is a front elevation of one form of automatic controlling apparatus embodying the invention, and showing the parts in normal positions;

Fig. 2 is a vertical transverse sectional view on line 2—2 of Fig. 1;

Fig. 3 is a vertical longitudinal sectional view through the switch on a larger scale and showing it as having been actuated to close the circuit, the section being taken on line 3—3 of Fig. 4;

Fig. 4 is a top plan view of the switch unit;

Fig. 5 is a sectional view on line 5—5 of Fig. 4 showing more clearly the switch rod tensioning means;

Fig. 6 is a detail elevation of the lower end of the control member and showing its yieldable connection as well as features of adjustment;

Fig. 7 is fragmentary view similar to Fig. 6 with the parts in different relationship;

Fig. 8 is a vertical sectional view on line 8—8 of Fig. 2;

Fig. 9 is a diagram of the electrical circuit in which the switch is connected; and

Fig. 10 is a fragmentary elevation, partly in section, of a modified form of switch.

The invention has been shown in the drawings as embodied in a damper regulator for steam boiler installations, but it is to be understood that it is not restricted to this use, since the salient features may be employed with equal advantage in many other environments. The improved damper regulator includes a pressure gauge A, switch actuating mechanism B, follow-up switch C, electric motor D, and damper actuating means E, all preferably enclosed and supported within a suitable casing F.

The gauge A is of the conventional type having a diaphragm 15 the lower side of which is acted upon by steam from the boiler (not shown) through a pipe 16. The upper side of the diaphragm acts against a knife edge 17 which supports a lever or beam 19, said beam being fulcrumed at 20 at one of its ends, and provided with suitable balance weights 21 adjacent its other end. The beam 19 may preferably extend outwardly through a slot 22 in the end wall 23 of the casing F, the balance weights being suspended on the beam at a point outside of the casing. Within the casing F are a pair of spaced lugs 24, 24 respectively disposed above and below the beam 19, and each provided with a set screw 25 forming abutments to limit the movement of the beam. When the weights 21 are properly adjusted, the beam will maintain a normal position as shown in Fig. 1 under the desired steam pressure against diaphragm 15, and variations or fluctuations in said steam pressure will cause the beam to raise or lower as the case may be. Such movements, beyond predetermined limits, are transmitted by the switch actuating mechanism B to the switch C, closing an electric circuit to cause rotation of the shaft 26 of motor D. The shaft 26 is provided with a worm 27 meshing with a worm wheel 28, which is held between bearings 29 and having an internally threaded hub 30 through which slide rod 31 of the actuating means E passes. The rod 31 has a threaded portion 32 in operative engagement with the internal thread of the hub 30, and is suitably held against rotation, whereby rotation of the worm wheel 28 will result in sliding movement of the rod 31. The motor D is reversible and the switch C is of the two way type, whereby the rod 31 will be moved to either the right or to the left, looking at Fig. 1, in accordance with the direction of rotation of the shaft 26. The rod 31 extends longitudinally through the casing F and is supported by the bearings 29 and by a bearing boss 33 in the casing wall 23. The outer end of the rod 31, beyond the wall 23 is connected as by a chain 34 or otherwise, to the device to be ultimately actuated, in this case a damper which is not shown in the drawings.

A switch supporting member 35 is secured

to the rod 31 by means of a set screw 36, and is formed with an upwardly extending arm 37 and a downwardly extending arm 38 which are preferably disposed in a plane behind the rod 31. The arm 38 bears against a relatively narrow longitudinal rib 39 on the back wall 40 of the casing F, and the arm 37 carries a set screw 41 whose extremity extends through said arm 37 and bears against a similar rib 42 parallel with the rib 39. The ribs 39 and 42 are disposed on opposite sides of the rod 31 as shown in Figs. 1 and 2, and by virtue of their engagement by the arm 38 and screw 41, the rod 31 will be held against rotation, yet the friction will be reduced to a minimum. The set screw 41 provides a convenient adjustment to compensate for wear of the parts.

The switch C is carried by the supporting member 35 and includes a mounting plate 43, of substantially rectangular outline, secured by screws 44 to the arm 38. By referring particularly to Figs. 2 to 5 inclusive, it will be seen that in the illustrated embodiment of the invention, the mounting plate 43 is disposed in a vertical plane spaced from the back wall 40 of the casing, and that the component parts of the switch are carried by said plate as a sub-assembly of the complete controller unit. Extending forwardly from the plate 43 are a pair of shelf brackets 45 which support a shelf 46 having a plurality of switch terminals. The shelf 46 may preferably be formed of dielectric material such as hard rubber, bakelite, fiber or the like, and also by preference, the switch terminals are in the nature of mercury wells. In this construction, the shelf 46 is provided with three recesses 47, 48, and 49 in which are set cups 50, 51, and 52 as best shown in Fig. 3. Said cups contain mercury or some other suitable liquid conductor, and they are respectively connected by wires 53, 54, and 55 to suitable binding posts 53^a, 54^a, and 55^a.

Secured to the shelf 46 and extending upwardly at the front edge thereof is an angle plate 56, between which and the mounting plate 43 a rockable frame 57 is supported. The rockable frame 57 may be conveniently formed of sheet metal or the like and includes a substantially horizontal portion 58 having, at its front and rear ends, upwardly extending ears 59 and 60, pivotally mounted on trunnions 61 and 62 respectively. Carried by the horizontal portion 58 are a pair of clamping blocks 63 and 64, of insulation material, between which is a longitudinally extending switch rod 65, said rod 65 being disposed over the mercury cups 50, 51, and 52. Intermediate its ends and adjacent to the clamping blocks 63 and 64, the rod 65 is provided with a brush or finger 66 which extends downwardly into the mercury in the central cup 50, and the proportions are such that said finger 66 always

remains in the mercury of said cup 50 regardless of the position of the rockable frame and switch rod. Adjacent each of its ends, the switch rod 65 is provided with adjustable tungsten contacts 67 and 68 which are respectively adapted to dip into the mercury in cups 51 and 52 as the switch rod is tilted in either one direction or the other to cause the motor to rotate in either direction as will hereinafter be explained.

Extending forwardly from the upper end of the ear 59 are a pair of spaced lugs 69 and 70 provided respectively with aligned adjusting screws 71 and 72. The inner ends 15 of the screws 71 and 72 oppose each other in spaced relation, and are adapted for abutment of a relatively thin flat blade 73 on the upper end of a swinging lever or control member 74 of the switch actuating mechanism B. Variations in the steam pressure beyond predetermined limits or other condition to be governed, causes the control member 74 to swing against either the screw 71 or screw 72 rocking the frame 57 and correspondingly tilting the switch rod 65 to close the circuit through either the mercury cup 51 or 52. In order to maintain the switch rod in its several positions and to accelerate its movements, the rockable frame 30 57 is provided with an angle bar 75 which extends substantially parallel with the switch rod 65 and is secured to the ear 60 by screws 76. At one of its ends, the bar 75 is provided with an enlarged head 77, the 35 edge of which is serrated to form inclined surfaces 78, 78 and 79, 79, the portions 79, 79 forming a recess 80 while the portions 78 and 79 define points 81 and 82 from which the portions 78 diverge. An arm 83 is pivoted at 84 on the mounting plate 43, and is provided at its upper end with a roller 85 which is pressed against the serrated edge of the head 77 by virtue of an adjustable weight 86 on an arm 87 which extends from 40 the arm 83. When the switch is in its normal position, as indicated in Fig. 5, with both contacts 67 and 68 out of the mercury, the roller 85 will be at the bottom of the recess 80, offering sufficient resistance to maintain the switch rod 65 in a level condition. As the frame 57 is rocked by the control member 74, one or the other of the points 81 or 82 passes the roller 85, whereupon said roller comes into engagement with the corresponding edge 78 of the head 77, imparting a cam action to quicken the movement of the frame 57. The frame 57 then remains in such tilted position until it is again actuated, in the opposite direction, by the 45 control member 74, at which time the acceleration takes place when the roller 85 engages the corresponding edge portion 79.

The switch actuating mechanism B is secured to the back wall 40 of casing F by means of a supporting bracket 88 which sup-

ports a transverse horizontal shaft 89 on trunnions 90 and 91. Adjacent its lower end, the control member 74 is provided with a pair of spaced bearing bosses 92 and 93, which are connected together by an inwardly or rearwardly extending web 94. The bearing bosses 92 and 93 receive the shaft 89, and are capable of rotation thereon, and are held against longitudinal movement by a pair of bushings 95 and 96 which are keyed, pinned or otherwise secured to the shaft. The bushing 96 may preferably be widened and formed on its lower edge 97 with a relatively straight cam surface which normally engages against a yieldable flat plate 98 which extends rearwardly below the bearing boss 93. The said boss 93 is similarly flattened on its lower edge, as best shown in Fig. 8, and provided with a pair of location pins 99 which loosely register with apertures in the plate 98. A plurality of retractile springs 100 have their lower ends connected at 101 to the opposite side edges of the plate 98, and their upper end attached to lugs 102 extending from the web 94, and said springs draw the plate 98 upwardly forming a yielding connection between the control member 74 and the shaft 89.

Extending radially from the bushing 96 and secured thereto is a channel member 103 provided with a series of openings 104 to 108 inclusive, all different distances from the center of the shaft 89, and connected to any one of said openings is the lower end of a link 109. The upper end of the link 109 is attached to the beam 19, preferably by means of a flat spring 110 which may be adjustably clamped by a screw 111 in a retaining member 112 on the rear side of the beam. The spring 110 permits adjustment of the lower end of link 109 to any desired one of the holes 104 to 108 whereby to determine the actuating limits of the mechanism. In this way movement of the beam 19 about its center 20 will be communicated to the switch actuating mechanism causing the control member 74 to swing in one direction or the other about the axis of shaft 89. The amplitude of movement of the control member 74, in proportion to that of the beam 19, is dependent upon the leverage of the channel member 103, and its play between the ends of the screws 71 and 72 may be varied by adjusting said screws toward or away from one another. From this it follows that the device can be very finely adjusted to permit any desired range of fluctuations in the conditions to be governed, and it is extremely sensitive and dependable in its actions.

Any suitable counter-weight 113 may be secured or attached to the control member 74 at a point below the shaft 89 in order to normally maintain the control member in a substantially vertical position.

By reference to Figure 9 the wiring connections for the device will be explained. In

this diagram the switch C has been illustrated as being disposed in a control circuit whereby to control the actuation of the main motor switches G, H, said switches being actuated by electro-magnets I, J. As has been previously stated the motor D is reversible and therefore the two switches G and H are required in order to reverse the electric current passing through the various conductors. The current is supplied through conductors 115 and 116 between which the field 117 of the motor D is connected. The conductor 115 is further connected by a wire 118 to the switch poles G¹ and H¹ and the conductor 116 is similarly connected by a wire 119 to the switch poles G² and H². The electro-magnets I and J are connected in series with each other and the individual magnet I is connected by the wire 120 to the mercury cup 52 of switch C, while the magnet J is connected by a wire 121 with the mercury cup 51 of switch C. The central mercury cup 50 is connected by a wire 122 with the main feed wire 115 and the electrically connected sides of the magnets I and J are connected by a wire 123 to the main feed 116. The switch points G³ and H⁴ are connected by a conductor 124 to one side of the armature of the motor D, while the switch points H³ and G⁴ are similarly connected to the opposite side of said armature. The result is that if the switch G is closed, the electric current will flow to rotate the armature of motor D in one direction and when said switch G is opened and switch H closed, the motor will rotate in the opposite direction. The switches G and H are opened and closed by the follow up switch C of the improved controller mechanism. The switch G being closed by the electro-magnet I when the switch rod is tilted to close the circuit through the mercury cup 52 and the switch H being closed by the electro-magnet J when the switch rod is tilted in the opposite direction, that is when the circuit is closed through the mercury cup 51.

When the improved controlling mechanism is installed, the balance weight 21 is first properly adjusted to determine the position of the beam 19 under the influence of the diaphragm 15. The link 109 is then connected to the desired opening in the channel 103 whereby to determine the range of fluctuations which are to be permitted in the installation. This adjustment of course must take into consideration the distance between the ends of the adjusting screws 71 and 72 on the rockable frame 57. When the steam pressure in the boiler is at the desired limit, the control member 74 and the carriage with the switch C and associated parts will be in relative positions as shown in Figure 1. As the steam pressure increases, the beam 19 is pushed upwardly by the knife edge 17 and said movement is communicated by the link

109 to the control member 74. If such movement goes beyond the predetermined limit of fluctuation, the blade 73 of the control member will engage the end of the screws 71 tilting the rockable frame 57 to a position, as shown in Figure 3. The electric circuit is then closed through the mercury cups 50 and 51 which influences the electro-magnet J to close the switch H, exciting the armature of the motor and correspondingly rotating the motor shaft 26. The rotation of the motor shaft 26 is communicated to the worm wheel 28 and because of its threaded engagement with the actuating rod 31 it results in rectilinear movement of said actuating rod, carrying with it the movable switch C. As movement of the actuating rod 31 continues the screw 72 is caused to engage the opposite side of the blade 73, tilting rockable frame 57 in the opposite direction from that in which it had been previously tilted by the control member and thus returning said rockable frame to its original position with the electric circuit broken at both of the mercury cups 51 and 52. At the same time as the switch C has been bodily moved against the control member, the damper of the boiler has been partially closed by virtue of its chain connection 34 with the actuating rod 31, and such movement should presumably be sufficient to compensate for the fluctuation in pressure which resulted in raising the beam 19. In a similar manner, if the steam pressure in the boiler drops beyond the predetermined limit, the beam 19 will move downwardly causing the control member 74 to move in a clockwise direction as viewed in Figure 1 closing the circuit through the mercury cups 50 and 52 to energize the electro-magnet I which in turn closes the switch G to rotate the motor D in the opposite direction. The actuating rod 31 will then be moved to the right as viewed in Figure 1 to increase the damper opening and to again reset the switch C as has previously been described. The permissible movements of the various parts may be much or little, as desired, and the results are quickly effected in a thoroughly dependable and efficient manner. It is to be noted that in some industrial applications controlling mechanism of this character are required to maintain the steam pressure or the like within a range of two or three pounds, while in other installations, greater variations are permissible. In view of the features of adjustment present in this improved regulator, it will function equally well regardless of the local conditions in the plant in which it is installed.

In Figure 10 a modified form of the invention has been shown as including an insulation tube 125 usually formed of glass or the like and sealed at both ends. The tube may preferably be of arcuate formation having a pivotal center in line with the trunnions

60 and 61 of the rockable frame 57 and supported in depending position from said frame by suitable radial arms 126. Disposed at opposite sides of the vertical center of the tube 125 are two pairs of electrodes 127, 128 and 5 129, 130 which extend into said tube, as clearly shown, and being connected to the carriage terminals 53^a, 54^a and 55^a. A drop of mercury 131 is confined within the tube 125 and capable of movement therein in such a manner 10 that as the rockable frame 57 is tilted to one side or the other, said drop of mercury will close the electro-circuit between the electrodes 127 and 128 or between the electrodes 129 and 130. The functions of this switch and 15 its connections in the motor circuit may be identical with those previously described with reference to the first embodiment of the invention and therefore more detailed description 20 is considered unnecessary.

It will be evident from the foregoing that a substantial advance has been made in the art by providing a circuit controlling device which will be extremely simple in construction and sensitive and reliable in operation. 25 Obviously the invention is susceptible of numerous modifications in the details of construction and arrangement of parts, and the right is herein reserved to make such changes 30 as fall within the scope of the appended claims without departing from the spirit of the invention.

It will be clear to those skilled in the art, that instead of an electric motor, a gas engine, 35 or a steam engine, or other suitable motor may be employed in the broader aspects of the present invention, in which specific instances of motor substitution, there could be substituted for the switch a control for the 40 power transmission of the gas engine, and in the case of a steam engine suitable valve mechanism could be substituted for the switch.

What I claim as new is:

45 1. In a regulating mechanism, a prime mover, a slidable actuating rod operable in one direction or the other therefrom for effecting predetermined movement of a governing device, mechanism including a 50 slidable carriage attached to the actuating rod for movement therewith, means on the carriage for regulating supply of power to the prime mover, a control member adapted to 55 actuate said power regulating means, said control member being influenced by conditions to be governed, and means for varying the ratio of movement of the control member with reference to the slidable carriage.

60 2. In a device of the character described, a balance beam, an oscillatory lever, and means for transmitting motion from said beam to said lever, said means including an arm pivoted with the lever, a link pivotally 65 connected with the free end of said arm, and

resilient means connecting said link to the beam.

3. In a device of the character described, a balance beam, an oscillatory lever, and means for transmitting motion from said beam to said lever, said means including a radial arm pivoted with the lever, and a resilient link connecting said arm with the beam. 70

4. In a device of the character described, a balance beam, an oscillatory lever, and means for transmitting motion from said beam to said lever, said means including a radial arm pivoted with the lever, and a link 75 adjustably connected between said arm and the beam. 80

5. In a device of the character described, a balance beam, an oscillatory lever, and means for transmitting motion from said beam to said lever, said means including 85 means for adjustment whereby to vary the ratio of movement between the lever and the beam.

6. In a device of the character described, a balance beam, an oscillatory lever, and means for transmitting motion from said beam to said lever, said means including an 90 arm yieldably mounted for movement with and with reference to the lever, and an adjustable link connection between the beam 95 and the lever.

7. In a regulating mechanism employing a reversible motor and a slidable actuating rod operable in one direction or the other therefrom for effecting the predetermined movement of a governing device, switch mechanism comprising a slidable carriage and movable means thereon for controlling the motor, said carriage being attached to the actuating rod for movement therewith, and a control member influenced by conditions to be governed by the device, said control member being adapted to actuate the switch at predetermined limits of movement. 100

8. In a regulating mechanism employing a reversible motor and a slidable actuating rod operable in one direction or the other therefrom for effecting the predetermined movement of a governing device, switch mechanism comprising a slidable carriage and movable means thereon for controlling the motor, said carriage being attached to the actuating rod for movement therewith and a control member influenced by conditions to be governed by the device, said control member being adapted to actuate the switch at predetermined limits of movement, and being adjustably connected whereby to vary 110 said limits as desired. 115

9. In a regulating mechanism employing a reversible motor and a slidable actuating rod operable in one direction or the other therefrom for effecting the predetermined movement of a governing device, a slidable carriage suspended on the actuating rod and 120 125

having the same amplitude of movement as said rod, movable switch means on the carriage for controlling the motor, and a control member influenced by conditions to be governed by the device, said control member being adapted to actuate the switch at predetermined limits of movement.

10. In a regulating mechanism employing a reversible motor and a slidable actuating rod operable in one direction or the other therefrom for effecting the predetermined movement of a governing device, a slidable carriage, a bracket carried by the actuating rod and supporting said carriage for movement with said rod, stationary means engaging said bracket to prevent rotation of the actuating rod, movable means on the carriage for controlling the motor, and a control member influenced by conditions to be governed by the device, said control member being adapted to actuate the switch at predetermined limits of movement.

11. In a regulating mechanism employing a reversible motor and a slidable actuating rod operable in one direction or the other therefrom for effecting the predetermined movement of a governing device, switch mechanism including a slidable carriage suspended on the actuating rod and having the same amplitude of movement as said rod, a plurality of mercury wells on the carriage forming circuit terminals, a rockable switch-rod on the carriage for making and breaking the circuit between said mercury cups, and a control member influenced by conditions to be governed by the device, said control member being adapted to rock the switch-rod and thereby to actuate the switch at predetermined limits of movement.

12. In a regulating mechanism employing a reversible motor and a slidable actuating rod operable in one direction or the other therefrom for effecting the predetermined movement of a governing device, switch mechanism comprising a slidable carriage suspended on the actuating rod and having the same amplitude of movement as said rod, a plurality of mercury wells on the carriage forming circuit terminals, a rockable switch-rod on the carriage for making and breaking the circuit between said mercury cups, said switch-rod being provided with adjustable contacts for dipping into the mercury cups, and a control member influenced by conditions to be governed by the device, said control member being adapted to rock the switch-rod and thereby to actuate the switch at predetermined limits of movement.

13. In a regulating mechanism employing a reversible motor and a slidable actuating rod operable in one direction or the other therefrom for effecting the predetermined movement of a governing device, switch mechanism including a slidable carriage and movable means thereon for controlling the motor,

means for communicating fluctuations in the conditions to be governed, an oscillatory lever adapted to actuate the switch, and a resilient link forming a connection between said communicating means and the oscillatory lever.

14. In a regulating mechanism employing a reversible motor and a slidable actuating rod operable in one direction or the other therefrom for effecting the predetermined movement of a governing device, a slidable carriage, a bracket carried by the actuating rod and supporting said carriage for movement with said rod, movable switch means on the carriage for controlling the motor, a control member influenced by conditions to be governed by the device, said control member being adapted to actuate the switch means at predetermined limits of movement, and a protective casing enclosing and supporting the mechanism, a portion of said casing engaging said bracket to prevent rotation of the bracket.

15. In a regulating mechanism, an electric motor, an actuating rod operating in one direction or the other therefrom for effecting predetermined movement of a governing device, switch elements associated with said rod and movable therewith for regulating supply of power to the electric motor, a control member movable relative to and with said switch elements to actuate the same to make and break the circuit, said control member being influenced by conditions to be governed, and means for varying the relative movement between said control member and said switch elements.
